UNITED STATES PATENT OFFICE.

ALBERT T. REID, OF LEAVENWORTH, KANSAS.

BABY JUMPER.

Application filed November 29, 1922. Serial No. 604,078.

To all whom it may concern:

Be it known that I, ALBERT T. REID, a citizen of the United States, residing at Leavenworth, in the county of Leavenworth 5 and State of Kansas, have invented certain new and useful Improvements in Baby Jumpers, of which the following is a specification.

My invention relates to improvements in 10 amusement devices for babies or children, and has particular reference to such a device serving as an exerciser, commonly termed a baby jumper.

An important object of the invention is 15 to provide a device of the above mentioned character, which is extremely light, strong, durable, inexpensive to manufacture, portable, and may have its parts readily separated so that they may be shipped in a compact manner.

Other objects and advantages of the invention will be apparent during the course of the following description.

In the accompanying drawings forming a 25 part of this specification, and in which like numerals are employed to designate like parts throughout the same,

Figure 1 is a perspective view of a device embodying my invention,

30 Figure 2 is a side elevation of the upright, and,

Figure 3 is a side elevation of the upper swinging frame, parts being broken away.

In the drawings, wherein for the purpose 35 of illustration is shown a preferred embodiment of my invention, the numeral 5 designates a lower stationary frame as a whole, preferably formed of a flat board 6, having a large longitudinal opening 7 cut therein, providing spaced diverging arms 8, preferably integral with the board 6. This makes for lightness, while imparting to the device suitable strength. Extending across the arms 8 is a relatively thin and light 40 bottom member or board 9, rigidly attached to the arms 8, by any suitable means.

The numeral 10 designates an upright, 45 provided at its lower end with a depending tongue 11, forming shoulders 12. The tongue 11 projects into the opening 7 and engages the side walls of the arms 8. This tongue has a longitudinal opening 13 formed therein, for receiving a transverse pin or rod 14, passing through openings in the 50 arms 8. Diagonal braces 15 are detachably

connected with the brace 10, near their center, by means of screws 16 or the like, while the lower ends of the braces 15 are detachably connected with the board 6 and the arms 8, by any suitable means. It is preferred that this connection be detachable, in order that the braces may be separated from the bottom or stationary frame 5, and the parts arranged in a flat or close relation, for shipment, as is obvious. The upright 10 is provided at its top with a rounded end 18, having vertical slots 19 therein. This rounded end also has a longitudinal opening 20, for the reception of a pivot element or pin 21.

The numeral 22 designates an upper swinging frame, as a whole, preferably formed of a flat board 23, having a large longitudinal opening 24 cut therein, forming longitudinal spaced diverging arms 25. The free ends of these arms are connected by a transverse member 26. Depending from the arms 25 near and spaced from the board 23 are eye-bolts 27, engaging therewith, and projecting into the slots 19, and pivotally receiving the pin 20. This construction is particularly advantageous, as the pivotal connection is entirely covered so that the babies fingers cannot have access thereto, while operating the device, and hence the liability of the fingers being pinched is very remote. The curved surface of the end 18 contacts with the arms 25 and serves to carry the load, while the eye-bolts 27 effect a suitable pivotal connection between the upper frame and the upright 10.

The numeral 28 designates a suitably stiff retractile coil spring, having its lower end provided with a hook 29, to engage in selected spaced eye-bolts 30, attached to the board 5, as shown. At its upper end, the spring 28 has connection with a bolt 31, projecting through a longitudinal slot 32 and carrying a winged nut 33. It is obvious that the spring 28 may be adjusted toward and away from the upright 10 and also the tension of the spring may be regulated by turning the nut 23.

The numeral 34 designates a seat for the 105 baby or child, depending from the free end of the arms 25. This seat is preferably formed of canvas or some other suitable material which may readily be washed, for sanitation. The seat 34 embodies sides 35 110

and an end 36. These sides and ends are passed about the arms 25 and transverse member 26 and may be detachably secured thereto by any suitable means. I may employ headed studs 37 secured to the frame, for insertion within button holes or openings formed in the sides and end 36, as is obvious. Any suitable means may be employed for this purpose. Secured to the 10 bottom of the seat is a strap 37', extending upwardly and providing openings 38, through which the child may insert his legs. The strap 37' is detachably connected by any suitable means with a tray 39, secured 15 to the arms 25, as shown.

In use, the baby or child is placed within the seat 34, and his legs extend downwardly through the openings 38 so that his feet may engage the bottom or floor member 9. 20 The child is therefore supported by the upper frame at a point beneath the frame and there is practically no liability of the device turning over. The child may raise and lower himself, and this will cause the 25 upper frame to swing upon its pivot. It is obvious that I have provided a device which will enable the child to partake of proper exercise, in an interesting and amusing manner, without liability of injury.

30 It is to be understood that the form of my invention herewith shown and described is to be taken as a preferred example of the same, and that various changes in the shape, size, and arrangement of parts 35 may be resorted to without departing from the spirit of my invention, or the scope of the subjoined claim.

Having thus described my invention, I claim:

In a baby jumper, a lower stationary frame embodying a body portion having spaced arms extending longitudinally from one end of said body portion and forming an opening between said arms, an upright provided at its lower end with a tongue extending between said arms within said opening, said upright being provided at its top with a rounded head and spaced substantially vertical slots and an opening extending longitudinally through said rounded head and passing through said slots, a transverse pin passing through said tongue and arms of the lower frame, an upper frame similar to the lower frame end embodying a body portion carrying spaced longitudinal arms at one end thereof, said arms forming an opening therebetween of sufficient width for the reception of a child, the arms of the upper frame resting upon said rounded head, eye-bolts depending 60 from the arms of the upper frame and arranged within said slots, a pivot element passing through the longitudinal opening in the head and through said eye-bolts, braces connecting the upright and lower 65 frame, a yielding element connecting the upper and lower body portions, and a flexible seat element suspended from the arms of the upper frame, said last named arms constituting the sides of the seat. 70

In testimony whereof I affix my signature.

ALBERT T. REID.
